Attorney

UNITED STATES PATENT OFFICE

CARL F. BIERBACH, OF PROVIDENCE, RHODE ISLAND

PENCIL SHARPENER

Application filed July 9, 1927. Serial No. 204,607.

This invention relates to an improved pencil sharpener and more particularly a device of this character provided with a detachable blade and so constructed as to permit the removal of a blade when dulled and its replacement by another.

One object of the invention is the provision of an improved device of this character having the cutting blade detachably secured to the sharpener whereby the cutting blade may be readily removed and replaced by another when desired.

Another object of the invention is the provision of an improved device of this character which may be cheaply and easily constructed and which is provided with a holder plate of ornamental form adapted in conjunction with the sharpener to simulate the appearance of an aeroplane.

20 A further object of the invention is the provision of novel means for firmly holding the cutting blade and other parts of the mechanism against movement relative to each other and thereby provide a firm and rigid structure which is of simple construction and highly efficient in use.

Other objects and advantages of the invention relate to various improved details of construction and arrangement of the parts as will 30 be more fully set forth in the detailed description to follow.

Referring to the drawings:—

Fig. 1 is a perspective view of the pencil sharpener.

35 Fig. 2 is an inverted plan view of the structure shown in Fig. 1, and illustrating the position of the parts upon the side opposite to that shown in Fig. 1.

Fig. 3 is a transverse sectional view taken 40 along the line 3—3 of Fig. 1.

Fig. 4 is a second transverse sectional view of a portion of the structure, taken along the line 4—4 of the Fig. 1, and,

45 Fig. 5 is a disassembled perspective view of the conical shell and projecting plate together with the cutting blade, and illustrating the means for detachably connecting the cutting blade to the projecting plate.

In the drawings 1 designates generally the 50 holder member which is formed from a single

metal plate by bending over the extended side edges 3 in such a manner as to cause these portions to overlie and impart added rigidity to portions of the main body of the holder 1. The outer portions 4 of the inturned edges 55 3 are bent into substantially close engagement with the main body portion of the holder as best shown in Fig. 3 of the drawings, while the innermost portions 5 of said inturned edges are spaced somewhat from the main 60 body portion of the holder to form grooves 6 and 7 located upon opposite sides of the slot 2. Adjacent to one end of the holder 1 are oppositely positioned downwardly extending plates 8 and 9 preferably formed integral 65 with the main body portion of the holder 1 and cut away from the main body portion of the holder throughout a part of their extent and then bent downwardly to form a channel space 10 for the reception of the 70 cylindrical portion 12 of a conical shell 14. The plates 8 and 9 are bent to incline inwardly or to converge throughout their extent from the main body portion of the holder, as shown in Fig. 4, whereby they frictionally 75 engage and press against the cylindrical portion 12 of the conical shell when the parts are in assembled position for a purpose which will be more fully set forth hereinafter.

At the opposite end of the holder 1 from 80 the plates 8 and 9, the width of the holder 1 is reduced as indicated at 15, and portions of the holder body 1 are bent in the opposite direction from the plane of the holder from that occupied by the plates 8 and 9 to form 85 jaws 16 and 17 for holding therebetween an eraser 18.

The pencil sharpener structure comprises 90 a conical shell 14 having a cylindrical portion 12 extending from the larger end thereof, as stated, and which may be formed from a metal sheet rolled into the desired shape and provided with a slot 20 extending in a longitudinal direction relative to the axis of the conical shell. A projecting plate 23 extends outwardly from one side of the slot 20 and is substantially tangential to the conical surface of the sharpener. A smaller plate 95 24 may be provided to extend outwardly from the opposite side of the slot 20. The project- 100

ing plates 23 and 24 are adapted to fit within the grooves 6 and 7 respectively, when the parts are in assembled position, whereby the slot 20 registers with the slot 2 in the holder plate, and the cylindrical portion 12 of the sharpener projects between and is frictionally engaged by the converging plates 8 and 9 to hold the cylindrical portion 12 against expansion due to the pressure of the pencil 10 therein.

When the conical shell 14 is formed from a plate of flat stock rolled into the desired form the meeting edges of the material are located at 21, and when a pencil is inserted in the conical shell there is a tendency for the cylindrical portion of the conical shell to spread along the line 21. The plates 8 and 9 converging downwardly from the holder 1 press closely against the opposite sides of the cylindrical portion 12 when the parts are in assembled position, thus tending to hold the cylindrical portion of the shell against spreading.

The projecting plate 23 is provided with two struck out lugs 25 and 26 which fit within openings 27 and 28 formed in the cutting blade 29 whereby the cutting edge 30 of the cutting blade 29 is held for proper engagement with the end of the pencil through the slot 20 of the conical shell. The groove 6 is so formed as to receive the projecting plate 23 and the cutting blade 29 carried thereby, and the innermost edge 31 of the inturned portion 3 may be bent downwardly to frictionally engage the upper face of the plate 23 and thus firmly bind the cutter in operative position. The plate 24 may be frictionally engaged in a similar manner at 31 to firmly bind the conical shell against sidewise movement in the holder. A depression 32 is 40 formed in the holder plate 1 adjacent to the end of the slot 2 to provide a space for the pencil point.

It will be seen that the grooves 6 and 7 provide means for receiving the plates 23 and 24 so arranged that the conical shell may be readily slid into position relative to the holder plate 1 so that the cylindrical portion 12 thereof will enter between the plates 8 and 9, and at the same time the cutting blade 29 underlying the plate 23 will be positioned in proper operative relation to the slot 20 and held against movement relative to the slot 20 and plate 23 by the pressure exerted thereon by the portion 5 of the inturned edge 3. 55 While the pressure upon the plate 23 and cutting blade 29 is sufficient to hold the blade against movement relative to the plate, it is not so great as to prevent removal of the conical shell 14, which may be removed from the holder whenever it is desired to substitute a new blade 29 for one which has become worn. In this way a structure is provided wherein the cutting blade may be removed and replaced by another whenever a change 65 of blades is desired, and at the same time the

parts are securely held against movement when in assembled position, thus insuring proper operation of the cutting blade at all times.

The appearance of the structure is such 70 as to simulate the form and general appearance of an aeroplane, the holder plate 1 being formed to resemble the wings of a monoplane, while the conical shell 14 and its cylindrical extension 12 resembles the fuselage, and the 75 narrowed portion 15 and eraser 18 correspond in appearance to the tail portion and rudder of an aeroplane respectively.

What I claim is:—

1. In a device of the character described, 80 a conical shell provided with an axially extending slot and having a projecting plate extending substantially tangential to the outer surface of said shell and located adjacent to the slot, a blade, means on said projecting plate detachably engaging said blade to hold the same in the cutting position relative to the slot, and a frame having a main body portion and a part thereof spaced from the main body portion to form a recess for 90 the reception of the projecting plate and blade, whereby the blade is retained in cutting position and held against separation from said engaging means.

2. A pencil sharpener comprising a conical shell provided with an axially extending slot and having a projecting plate extending substantially tangential to the outer surface of said shell and located adjacent to said slot, a cutting blade fitting against one side of said plate, means on said plate engaging portions of said cutting blade to retain the same in cutting position relative to said slot, a holder for said conical shell comprising guides engaging one end of the conical shell, and means 100 engaging said plate and cutting blade to retain the conical shell in position relative to the holder and hold the cutting blade detachably against separation from the plate.

3. In a device of the character described, 110 a conical shell having a cylindrical portion and provided with a slot extending longitudinally of the axis thereof, a projecting plate extending substantially tangential to the outer surface of said shell and located 115 adjacent to the slot, a cutting blade, a holder provided with a groove for the reception of said projecting plate and cutting blade and having a portion frictionally engaging said plate to hold the cutting blade firmly against the plate, and converging plates carried by 120 said holder and frictionally engaging opposite sides of the cylindrical portion of said conical shell to prevent spreading of the shell.

4. A pencil sharpener comprising a conical shell having a cylindrical portion at one end thereof and provided with a slot extending longitudinally of the axis thereof, projecting plates carried by said shell, one of which 130

is arranged substantially tangential to the outer surface of said shell and located adjacent to the slot, a cutting blade detachably secured to one of said plates, a holder having
5 a slot adapted to register with the first named slot when the parts are in assembled position, and having side edges inturned over the main body portion of the holder, the inner edges thereof being spaced from the main body portion of the holder to form grooves for the reception of the projecting plates, and down-turned end portions bent to form a channel for the reception of the cylindrical portion of said conical shell.

15 In testimony whereof I have affixed my signature.
